POWDER PUFF

John S. Vild, Pittsburgh, Pa.

Application December 11, 1939, Serial No. 308,694

3 Claims. (Cl. 132—78.5)

The invention relates to a powder puff and more especially to a powder-contained puff.

The primary object of the invention is the provision of a puff of this character, wherein a container for powder is built within the body of such puff so that when the latter is in use powder can be dispensed thereby for the convenient application of the same onto the face of a user of the puff and in this manner eliminating undue waste of the powder through application thereof in the usual well-known manner.

Another object of the invention is the provision of a puff of this character, wherein the container for the powder is of a collapsible formation and serving, when actuated, for the discharge of powder directly from the puff and in this way eliminating the necessity of acquiring the powder from a separate container as is customary.

A further object of the invention is the provision of a puff of this character, wherein the same in its construction is novel in the entirety, being such as to enable the carrying of the powder within the puff and for the application of the powder during the use of such puff.

A still further object of the invention is the provision of a puff of this character, which is simple in its construction, readily and easily manipulated for the placement of powder in the use of the puff, thoroughly reliable and efficient in operation, convenient for the carriage thereof upon the person or in wearing garments, the pocketbook or other place for convenient storage of the same, and inexpensive to manufacture.

With these and other objects in view, the invention consists in the features of construction, combination and arrangement of parts as will be hereinafter more fully described, illustrated in the accompanying drawing, which discloses the preferred embodiment of the invention and pointed out in the claims hereunto appended.

In the accompanying drawing:

Figure 1 is a plan view partly in section of a puff constructed in accordance with the invention looking toward the powder-applying side thereof.

Figure 2 is a sectional view on the line 2—2 of Figure 1 looking in the direction of the arrows.

Figure 3 is a view similar to Figure 2 showing the puff compressed for discharge or delivery of powder therefrom.

Figure 4 is an enlarged fragmentary sectional view taken through the powder container of the puff.

Similar reference characters indicate corre-

sponding parts throughout the several views in the drawing.

Referring to the drawing in detail, A designates generally a powder puff of the style employed by women for the application of powder to the person and comprises a textile body 5 made from a fabric section shaped into a bag, sack or the like, being circular in contour and having within a padding or filler 6 of loose cotton batting or other compressible puff forming material.

This body 5 exteriorly thereof is provided with a velvety or soft piled outer facing or surface 7 as is usual in the ordinary puffs for powder application, the body 5 being freely flexible for compressing of the filler 6 within and is shaped in addition to the circular formation thereof to have a slightly flattened characteristic.

Built within the body 5, preferably centrally thereof, is a powder container B comprising an extensible and contractible cylindrical body 8 for bellows-like action, carrying at an open end 9 thereof a removable cover or cap 10, being accessible exteriorly of the said body 5 and in this instance is detachably threaded at 11 to a mouth ring or rim assembly 12 fitted to the open end 9 of said body 8, while the other end 13 of the said body 8 has provided therein a plurality of discharge orifices or openings 14, this being the discharge or delivery end of the container B for the powder. The powder 15 is introduced into the body 8 through the open end 9 thereof on removal of the cap 10. The end 13 having the orifices or openings 14 has disposed thereover a wire mesh netting or screen 16 which is disposed in underlying relation to the body 5 at the area thereof next to the said end 13 of the body 8. This netting or screen 16 is sandwiched or placed between the body 5 and the end 13 of the body 8 and is held in such placement in any suitable manner. Within the body 8 is a coiled compression spring 17 being at rest against the end 13 and also against an in-turned annular flange 18 bent from the rim or ring assembly 12 and this spring 17 normally extends the body 8 as is clearly shown in Figures 2 and 4 of the drawing.

Now when pressure is applied to the cap 10 the body 8, which is of pliable material, will become partially collapsed or bellowed so that the powder 15 within the said body will be discharged through the orifices or openings 14 and this discharge of powder will seep through the body 5 for application to the skin of a person in the use of the puff. Thus the necessity for the dipping of the puff into a quantity of powder within a

container separate from said puff is entirely avoided so that the puff as before described will supply powder in the use of said puff and in the manner as hereinbefore set forth. The seepage of the powder through the body 5 takes place through the interstices of the fabric resultant from the weave of such fabric from which the body 5 of the puff is made.

The body 8 of the container B for the powder 15 is secured in place within the body 5 of the puff in any suitable manner, the said body 8 being extended through a clearance provided in one side of the puff body 5. The body 5 of the puff A can be internally reinforced or constructed from a material having the required stiffness yet inherently pliable or flexible so that in its association with the filler 6 there is created a compressible pad action in the using of the puff A for the application and spreading of powder upon the skin of a person.

The velvety or piled outer surface or face 7 of the body 5 renders the puff soft and avoids injury to the skin of a person in the use of said puff, this being common to the standard or well-known constructions of powder puffs.

The puff constructed as before described enables the carriage of powder within it and the application of the powder concurrently with the use of said puff to the skin of a person and in this way avoiding or eliminating the dipping of the puff into powder or otherwise application of the powder to said puff from a separate and independent container for the powder.

What is claimed is:

1. A puff of the kind described comprising a flexible body having an external velvety surface and flattened, a contractible container built within said body and having an open end and an opposite perforated end, the perforated end being arranged in confronting close relation to said body and the open end exposed exteriorly of the body, a cap removably fitted to said body for closing its open end, and compressible means within the container for normally extending the same.
- 15 2. A puff of the kind described comprising a flexible body having an external velvety surface and flattened, a contractible container built within said body and having an open end and an opposite perforated end, the perforated end being arranged in confronting close relation to said body and the open end exposed exteriorly of the body, a cap removably fitted to said body for closing its open end, compressible means within the container for normally extending the same, and a pliable filler within the body and about the said container.
- 20 3. The combination of a powder puff body, a substantially cylindrical compressible container built within said body for receiving powder and having a perforated discharge end confronting the said body for delivery of contents of said container through its perforations to without the body, the other end of said container being accessible for the filling thereof.

JOHN S. VILD.
